SAFETY DEVICE FOR LOCKS

Sophie S. Karavia, New York, N. Y.

Application June 11, 1940, Serial No. 339,864

9 Claims. (Cl. 70—425)

My invention relates to safety devices for locks and has particular reference to devices for preventing opening of door locks.

In certain establishments such as banks, stores, 5 workshops etc., the doors must remain closed and locked during the night, and there is usually a danger that an unauthorized person may obtain a key and gain admittance during the night. The same applies to private houses and apartments 10 when the occupants leave temporarily the premises, locking the outside doors.

My invention has for its object to provide a safety device which may be added to an ordinary lock for preventing insertion of a key into the 15 keyhole. I provide for this purpose a member supported outside the lock and adapted to be manually moved into a position in which the keyhole is closed so that the key cannot be inserted. The member is covered by a number of discs with 20 eccentric openings for the keyhole, the discs having means for locking the sliding member in a keyhole closing position. By placing the discs in a certain position which is known to the rightful owner of the key, the member is released and can 25 be withdrawn thereby exposing the keyhole. The discs may be provided with a plurality of symbols for indicating the operative positions in which the locking member is released.

My invention is more fully described in the 30 accompanying specification and drawing in which—

Fig. 1 is a sectional elevational view of my device in connection with a door lock;

Fig. 2 is a front view of the same;

Fig. 3 is a detail view of a keyhole closing member;

Fig. 4 is a detail view of a locking disc;

Fig. 5 is a rear view of a locking cylinder;

Fig. 6 is a detail view of a keyhole disc; and

Fig. 7 is a sectional view taken on the line 7—7 of Fig. 3.

My safety device is shown in the drawing as applied to a door lock 1 having a sliding bolt 2 with a handle 3 (shown partly broken away) at one side 45 and a locking cylinder 4 at the other, usually outer side, the lock being fitted in a door 5. A plate 6 is attached to the door on the outside by bolts 7 with concealed heads 8 so that the bolts cannot be unscrewed from the outside. The plate has an 50 opening 19 threaded for the threaded end 11 of the lock cylinder 4. The latter is also attached to the lock 1 by screws 12. A disc 13 is attached to the plate 6 by screws 14 passing through holes 15. The disc is provided with an opening 16 for the keyhole 17 in the lock cylinder. The opening 16

can be closed by a tongue 18 on a sliding bar 19 fitted in a corresponding slot in the disc 13. The member or bar 19 has a hook 20 on the end for manually moving the bar so as to open or close the keyhole. The disc 13 with the sliding bar is 5 covered by a number of discs 21, 22 and 23, rotatively held together on a bolt 24 fastened to the first disc 13 by a nut 25. A suitable recess 26 is provided in the lock cylinder 4 for the end of the bolt 24 with the nut 25. The lock cylinder is also 10 fastened to the disc 13 by screws 43. A ring 27 encloses peripherally the first disc 13 and is attached to the plate 6 by screws 28. It is provided with a slot for the end of the sliding bar 19. A second ring 29 is rotatively fitted in the first ring, 15 extending above the first ring and attached by screws 30 to the second disc 21. A third ring 32 is placed inside the second ring 29 and is fastened to a third disc 22 by screws 34. The ring 32 is tapered on the inside, slidably engaging the ta- 20 pered peripherally of a fourth disc 23.

Discs 21 and 22 are provided with two concentric slots each, 36 and 37, with an opening 38 between them, the slots being also concentric with the bolt 24 or its hole 39 (Fig. 4). The last disc 25 has grooves 40 and 41 corresponding to the slots in the discs 21 and 22. The bolt 24 has a round head 42 sunk into the last disc 23 so that it cannot be turned or unscrewed from the outside. To prevent the removal of the lock cylinder 4 it is 30 fastened to the disc 13 by screws 43 passing through holes 44.

The slots and the grooves are engaged by a pin 45 extending from the sliding bar 19. The pin 35 controls the position of the bar, the latter being 35 in the keyhole closing or operative position when the pin is placed in the slots 36 and groove 40 and in the keyhole opening position when placed in the slots 37 and groove 41. For moving the bar from one position to the other, the discs are 40 rotated until all their openings 38 are placed on a line with the axis of the sliding bar 19. Since the slots and grooves cannot be seen from the outside, the correct position of the discs is determined by 45 placing certain marks on their peripheries opposite a stationary mark 46 on the first ring 27. The rings are provided for this purpose with numerals 47, 48 and letters or other suitable symbols 49. For turning the outer disc 23 it is provided with a pin or screw 50, the inner discs being turned by 50 rotating their rings.

The discs have round openings 51 registering with the keyhole 17. The openings are closed by discs 52 with keyhole slots 53. The discs are retained in their position by their tapering periph- 55

eries engaged by correspondingly tapering sides of the openings 51 as shown in Fig. 1. These smaller discs protect the main keyhole from dirt etc.

- With my safety attachment it is impossible to
- 5 insert the key into the keyhole 17 of the lock cylinder if the pin 45 is placed in the outer slots 37. The rings can be turned with the pin in the outer grooves and slots without enabling the pin to pass into the inner grooves or slots 36. This may happen only if all the discs are aligned with the openings 38 in line with the pin 45 and bolt 24. This position of the discs cannot be found by trial and it is necessary to know the exact combination of the symbols 47, 48 and 49. When the discs are 10 correctly placed, the bar 19 is withdrawn by pulling on its hook 20. The bar may be then left in the open or inoperative position if desired, or it can be shifted again into the closing position, locking it by turning the discs in different directions.
  - 15 It is understood that my safety device may be modified without departing from the spirit of my invention as set forth in the appended claims.

I claim as my invention:

- 20 1. A safety device for a lock comprising a plate, means to support the plate in front of a keyhole of the lock, the plate having an opening registering with the keyhole, a manually operable member supported on the plate adapted in its operative position to close the keyhole for preventing insertion of a key, a plurality of discs 25 rotatively supported on the plate one on top of the other and overlapping the opening, the discs having openings registering with the keyhole in a certain position of the discs, and means on the 30 discs for locking the member in the keyhole closing position, the member being adapted to be manually withdrawn into the keyhole opening position when the discs are placed in a corresponding position, the discs having symbols for 35 indicating their positions.

- 40 2. A safety device for a lock comprising a plate, means to support the plate in front of a keyhole of the lock, the plate having an opening registering with the keyhole, a manually operable member slidably supported on the plate adapted to be moved for selectively closing and opening the keyhole, a plurality of discs rotatively supported on the plate one on top of the other 45 and overlapping the opening the discs having openings corresponding to the keyhole opening, a projection extending transversely from the sliding member, the discs having openings for the 50 projection, and cam-shaped portions on the discs 55 engaging the projection, one cam-portion corresponding to the keyhole closing position of the member and the other to the keyhole opening position, the discs having passages between the 60 two portions for moving the member, the discs having symbols for indicating their positions.

- 65 3. A safety device for a lock comprising a plate supported in front of a keyhole of the lock, the plate having an opening registering with the keyhole, a sliding member on the plate adapted to close the keyhole opening for preventing insertion of a key, a plurality of discs rotatively supported on the plate eccentrically with the keyhole and having openings registerable with the 70 keyhole, a pin extending from the sliding member, the discs having slots forming cam-shaped surfaces engaging the pin, the outer disc having grooves corresponding to the slots of the inner discs, each disc having a passage between its 75 two slots, one slot being inside the other, the

bar closing the keyhole opening when the pin is in the inner slots and opening the keyhole when the pin is in the outer slots, and means to indicate the positions of the discs.

4. A safety device for a lock comprising a plate 5 supported in front of a keyhole of the lock and having an opening registering with the keyhole opening, means to attach the lock to the plate, a sliding member on the plate adapted to be manually moved for selectively closing or opening the keyhole, a plurality of discs rotatively supported on the plate one on top of the other eccentrically with the keyhole opening, the discs having two concentric slots each, the outer disc having grooves corresponding to the slots, the inner and outer slots having a communicating passage therebetween, a pin extending from the sliding member engaging the slots, the member being in the keyhole opening position when the pin is in the outer slots and in the closing position when the pin is in the inner slots, the member being set free for movement between the slots when the discs are aligned with the slot 10 passages extending along the axis of the sliding member, and means to manually rotate the discs. 20

5. A safety device for a lock comprising a plate, means to support the plate in front of the keyhole of the lock, the plate having an opening registering with the keyhole a sliding member on the plate adapted to close the opening, a plurality 30 of discs on the plate, a bolt fastened to the plate and rotatively supporting the discs, rings on the peripheries of the discs successively and concentrically engaging each other, the discs having openings registerable with the keyhole opening, the discs being further provided with inner and outer slots, each pair of slots being in a communication with each other at one point, a pin extending from the sliding member passing through the slots, the bar being adapted to be manually shifted between its operative and inoperative positions for closing and opening the keyhole when the discs are manually turned into positions in which the communicating openings between the 45 slots are in line with the axis of the sliding member, the outer slots corresponding to the inoperative position of the member and the inner slots to its operative position, and movable discs for closing the keyhole openings in the discs.

6. A safety device for a lock comprising a plate supported in front of the keyhole in a lock cylinder, means to attach the lock cylinder to the plate, a movable member on the plate for closing the keyhole, a plurality of discs rotatively supported on the plate covering the movable member, the discs having arcuate slots, inner and outer, and a pin extending from the movable member into the slots, the inner and outer slots having a communicating groove the movable member being released for movement between its two extreme positions when the discs are placed in a position with the communicating slots in line with the axis of the member. 55

7. A safety device for a lock having a lock cylinder for operating a door bolt, comprising a plate, the lock cylinder being screwed into a hole in the plate, means to prevent unscrewing of the lock cylinder from the plate, a member slidably supported on the plate for selectively closing or opening the keyhole of the lock cylinder, a plurality of discs on the plate, a bolt mounted on the plate rotatively supporting the discs, the discs having openings registerable with the keyhole, the discs being provided with means 60 70 75

for permitting the movement of the sliding member in one position of the discs and for preventing said movement in other positions of the discs, and means to indicate different positions of the discs.

8. A safety device for a lock comprising a plate, means to attach the plate to a cylinder of the lock, the plate having an opening for the keyhole of the lock, a sliding member on the plate 10 adapted to be manually moved for closing or opening the keyhole, a plurality of discs covering the sliding member, the member having a handle extending outside the discs, the discs having inner and outer arcuate slots having a 15 communicating slot at one point, a pin extending from the sliding member passing into the slots, and means to manually rotate the discs for placing them into a position in which the communicating slots are in line with the line of movement of the sliding member thereby releasing the member for movement between its operative and inoperative positions, the member being prevented from movement when the discs are turned for disaligning the communicating slots.

9. A safety device for a lock comprising a plate, means to attach the plate to a cylinder of the lock, the plate having an opening for a keyhole of the lock, a sliding bar supported at the outer side of the plate, adapted to close the keyhole opening in its operative position, a plurality of discs on the plate covering the main portion of the sliding member, a bolt rotatively supporting the discs on the plate, the lock cylinder having a recess for the bolt, the discs having openings 10 registrable with the keyhole opening in the plate, the discs having two concentric arcuate slots each, a pin extending from the sliding member into the slots, each pair of slots having a 15 communicating slot, the sliding member being rendered free for movement between its operative and inoperative positions when the communicating slots in the discs are placed in line with the line of movement of the sliding bar, the pin being adapted to be retained in the inner or outer slots when the discs are rotated for displacing the communicating slots, and means on the discs for indicating their different positions.

SOPHIE S. KARAVIA.
